MARINE TIME SYSTEM

Allan C. Cargill, Vestal, N.Y., assignor to International Business Machines Corporation, New York, N.Y., a corporation of New York

Application March 5, 1957, Serial No. 644,125

6 Claims. (Cl. 58—26)

This invention relates to periodically supervised self-regulated time systems and to systems of this type adapted for marine or shipboard use and in particular to the secondary clocks associated therewith.

The invention pertains to clock systems wherein a master clock operates to send electrical impulses at regular intervals of time to all of the secondary clocks associated therewith in the system and each secondary clock is advanced a predetermined amount upon receiving each impulse. In addition to this, the master clock during certain predetermined intervals of time automatically regulates and effects synchronization with the master clock of any of the secondary clocks which may be fast or slow. A system of this type is disclosed, in U.S. Patent No. 1,687,491, issued October 16, 1928, to J. W. Bryce.

In time systems for use on land, the apparatus is fixed in location or remains in a definite time belt and the only correction or periodical change required is the relatively small occasional corrections arising from lack of isochronism of the pendulum, and the bi-yearly changes to and from daylight saving time.

In the case of time systems located on ships traveling on the high seas, during the course of each eastward or westward passage, it is necessary to make very material corrections of the clocks at rather frequent intervals, particularly in the case of fast vessels which require only a few hours to traverse a degree of longitude. With such a ship, the clocks would have to be advanced when traveling due east and retarded when traveling due west by one or two half-hour intervals per day.

An object of the present invention is to provide an automatically supervised self-regulating time system with controlling means enabling the system to be corrected when made necessary by the progress of a vessel easterly or westerly through different time belts or zones.

It is the object of the present invention to provide a supervised self-regulating time system in which the periodic or frequent corrections made necessary on shipboard may be effected more conveniently than heretofore.

Another object of the invention is to provide a supervised self-regulating marine time system with a more convenient and accurate method and means of setting the clocks of this system as a whole whenever a correction is required which requires advancing or retarding of the clocks an amount greater than can be accomplished by the usual self-regulating system.

A further object of the invention is to provide a secondary clock apparatus for a system of the type referred to which is of improved construction and arrangement of parts.

A still further object is to provide a secondary clock apparatus of the type which is composed of relatively few parts and which is relatively low in cost.

Other objects of the invention will be pointed out in the following description and claims and illustrated in the accompanying drawings, which disclose, by way of examples, the principle of the invention and the best mode,

2

which has been contemplated, of applying that principle.

In the drawings:

Fig. 1 is a rear elevational view of the movement for a secondary clock.

Fig. 2 is a partial vertical section on the line 2—2 in Fig. 1.

Fig. 3 is a wiring diagram for the secondary clock movement.

Fig. 4 is a clock system wiring diagram.

Fig. 5 is a partial rear view of the clock movement showing the drive mechanism in an energized position for a normal forward drive operation.

Fig. 6 is a partial rear view of the clock movement showing the reverse control mechanism in an energized position and the drive mechanism in a de-energized position for a reverse drive operation.

Fig. 7 is a partial rear view of the clock movement showing the reverse control mechanism in an energized position and the drive mechanism in an energized position for a reverse drive operation.

In all of the above-described views like characters of reference are employed to designate like parts throughout.

The preferred form of the invention as shown and described in this specification is directed to the operation of a self-synchronizing clock system such as is shown and described in the Patent No. 1,687,491, issued October 16, 1928, to J. W. Bryce, and the modifications thereto to adapt it for marine use. As shown in Fig. 4, the system comprises a master clock 10 and one or more secondary clocks 11. This type of system requires the use of four transmission lines, three of which are used to normally advance and self-regulate the secondary clocks, the fourth line is used to actuate the reverse drive controls.

It has been the practice, heretofore, to equip master clocks with certain contacts that cooperate with the clock movements to send impulses of electrical current to the secondary clocks at regular periods of time for the purpose of driving the secondary clocks and also to equip the master clocks with additional contacts for sending rapid impulses of current during the synchronizing period to any of the secondary clocks which may happen to be slow at the commencement of the synchronizing period. Conveniently, the source of current may be A.C. derived from the ship's light and power generators.

Since the master clock itself is of a well-known construction, it will not be described in great detail herein.

More particularly, the invention is directed to the improvements to the secondary clock movements which adapt them for use in a marine clock system.

50

Clock movement structure

Referring to Figs. 1 and 2, the front plate 14 carries the magnet system consisting of the two magnets 15 and 16 to which an oscillating armature 17 is coordinated. The yokes 18 and 19 of the magnets 15 and 16, respectively, are fastened to the front plate 14 by screws 20. The rear plate 21 and bridge member 22 are fastened to the yokes 18 and 19 by screws 23. Rear plate 21 is held in a spaced relationship with respect to the yokes 18 and 19 by means of suitable spacers (not shown). The shaft of oscillating armature 17 has its bearings in plate 14 and bridge member 22 and carries on its rear end a disc 24. Eccentrically and pivotally mounted on the disc 24 are the forward and reverse driving pawls 25 and 26, respectively, limited in their driving movement by the stop pieces 27 and 28, respectively, fastened to rear plate 21. The forward drive pawl 25 coacting with the stop piece 27 limits the forward drive rotation of the disc 24, which is normally biased counterclockwise by the spring 29.

Pivotedly mounted on the rear plate 21 is a bell crank 31 that is biased in a counterclockwise direction by spring

32 and which has rotatably mounted thereon a roller 33 adapted to detent the square-toothed ratchet wheel 30. The ratchet wheel 30 is provided with sixty teeth and is adapted to be advanced at a rate of one tooth per impulse in either a forward or reverse direction depending upon the state of the controls as will become apparent later in the description. The ratchet wheel 30 is fixed to the main arbor 34 which carries the minute hand. The hour hand is operated from this shaft by the usual well-known set of dial works or gear train.

Pivottally mounted on the main arbor 34 is a lever 35 to which is attached the studs 36 and 37. Lever 35 is normally biased in a clockwise direction by spring 38. An electromagnet 39 is attached to the rear plate 21 and has an armature 39a arranged to engage stud 37 for the purpose of moving lever 35 counterclockwise when electromagnet 39 is energized. The purpose of operation of lever 35 will become more apparent later in the description.

A single pole double throw switch 40 including an arm 40a and roller 40b is attached to the rear plate 41. The roller 40b is arranged to follow the surface of cam 41 that is attached to the main arbor 34. The switch 40, controlled by the chronological position of the clock movement, is used to transfer the connections of the magnets 15 and 16 with the A and B wires of the system during normal drive and self-regulating operations (Fig. 3). The C wire serves as the common return wire. The switch 40 controlled by the cam 41 is timed so that magnets 15 and 16 will be connected to the A wire when the secondary clock indicates from the 60 minute to the 59 minute positions and so that magnets 15 and 16 will be connected to the B wire, for one minute, from the 59th minute to the 60th minute position of the secondary clock.

Normal secondary operation

With the electromagnet 39 in a de-energized position, when the magnets 15 and 16 are energized the armature 17 is turned clockwise bringing the axis of said armature into position substantially parallel to the lines of magnetic flux which flow between the poles of the magnet as shown in Fig. 5. In taking this position additional tension is introduced into the spring 29 and the forward drive pawl 25 is moved to the right to engage the next right-hand successive tooth to the one previously engaged. When the magnets 15 and 16 are de-energized the tension of the spring 29 causes the armature 17 to be restored to its normal position (Fig. 1) and the forward drive pawl 25 is carried to the left rotating the ratchet wheel 30 counterclockwise one tooth position. The roller 33 engaging ratchet wheel 30 prevents retrograde movement of the wheel 30 when the forward drive pawl 25 is moved to the right on the next successive impulse. With lever 35 in its normal position stud 36, which controls the reverse pawl 26 prevents the same from engaging a tooth of ratchet wheel 30 in a driving manner during the oscillatory movement of armature 17.

Reverse secondary drive operation

With the electromagnet 39 in an energized position lever 35 will be moved to its counterclockwise position so that stud 36 underlies the forward drive pawl 25 (Fig. 6). When the magnets 15 and 16 are energized the armature 17 is turned clockwise bringing it into its energized position as shown in Fig. 7. In moving to this position, armature 17 carries with it reverse drive pawl 26 thereby moving ratchet wheel 30 clockwise one tooth position in a clockwise direction. When the magnets 15 and 16 are de-energized the tension of spring 29 causes the armature 17 to be restored to its normal position (Fig. 6) and the reverse drive pawl 26 is moved to the left to be in position to engage the next successive left-hand tooth in ratchet wheel 30 as shown by Fig. 6. The roller 33 engages ratchet wheel 30 in a detenting fashion. With lever 35 in its energized position stud 36 prevents the forward drive pawl 25 from engaging a tooth of ratchet wheel

30 in a driving manner during the oscillatory movement of armature 17.

System operation

5 The functioning of the system in the normal way as an hourly supervised self-regulating time system will now be described. Once each minute the master clock 10 (Fig. 4) transmits an impulse along the A wire. The minute impulses are conducted through the switch contacts 40c (Fig. 3) and energizes magnets 15 and 16 of the secondary unit completing the circuit through the C wire. The secondary clocks will be advanced one minute by each energization of magnets 15 and 16 during normal operation as described above. At the 59th minute position the secondary unit transfers its driving magnets from the A wire to the B wire via the switch contacts 40d.

10 There are three possible conditions which may exist with respect to any secondary clock in the system; it may be ahead of time, on time, or late. Thus, such secondary 20 units that are fast will reach the 59th minute position in advance of the master clock and will be transferred to a dead B wire and will therefore be halted until a minute impulse is sent through the B wire at the 60th minute. A series of rapid impulses are set out over the A wire between the 59th and 60th minutes so that all secondaries 25 that are slow and remain connected with the A wire will be advanced until they are in synchronism with all secondaries at the 59th minute position at which time they transfer themselves from the A wire to the B wire in readiness to be started off in unison when the 60th minute impulse is transmitted under the B wire at the 60th minute.

30 The setting back of the system is accomplished through the actuation of a switch in a master clock 10 which energizes the R wire (Fig. 4) causing the electromagnets 39 in each of the secondary units to be energized. Then by manipulation of switches in the master clock a series of rapid impulses, equivalent to the number of minutes desired to set the system back, are sent out over both the 35 A and B wires. The secondary clocks will be stepped one minute in the reverse direction for each impulse in accordance with the operation of the secondary clock as described above. Consequently, the clock system can rapidly be driven in the reverse direction equivalent to 40 15 minutes, 30 minutes or 60 minutes as desired.

45 It should be readily apparent that such a system in addition to shipboard use would have particular advantage to accommodate the bi-yearly changes to and from daylight saving time.

50 While there have been shown and described and pointed out the fundamental novel features of the invention as applied to a preferred embodiment, it will be understood that various omissions and substitutions and changes in the form and details of the device illustrated and in its 55 operation may be made by those skilled in the art, without departing from the spirit of the invention. It is the intention, therefore, to be limited only as indicated by the scope of the following claims.

What is claimed is:

60 1. In an electrically operated clock mechanism, the combination of an electromagnet, means for periodically energizing said electromagnet, a pivottally mounted armature adapted to be oscillated in response to the energization and de-energization of said electromagnet, time indicating means, a ratchet wheel connected to said time indicating means, a forward drive pawl and a reverse drive pawl pivottally and eccentrically mounted on said armature and adapted to coact with said ratchet wheel, a second electromagnet and means for selectively energizing 65 said second electromagnet, a pivottally mounted lever associated with said second electromagnet, and adapted to be actuated in response to the energization and de-energization of said second electromagnet, and a stud mounted on said lever and positioned relative to said drive pawls 70 whereby when said second electromagnet is in its normal 75

de-energized position the stud renders said reverse drive pawl ineffective as the ratchet wheel driving means during the oscillatory movement of said armature and when said second electromagnet is in its energized position the stud renders said forward drive pawl ineffective as the ratchet wheel driving means during the oscillatory movement of said armature.

2. In an electrically operated clock mechanism, the combination of an electromagnet, means for periodically energizing said electromagnet, a pivotally mounted armature adapted to be oscillated in response to the energization and de-energization of said electromagnet, a time indicating shaft, a ratchet wheel connected to said time indicating shaft, a forward drive pawl and a reverse drive pawl pivotally and eccentrically mounted on said armature and adapted to coact with said ratchet wheel, a second electromagnet and means for selectively energizing said second electromagnet, a lever pivotally mounted on said time indicating shaft and adapted to be actuated in response to the energization and de-energization of said second electromagnet, a stud mounted on said lever and positioned relative to said drive pawls whereby when said second electromagnet is in its normal de-energized position the stud renders said reverse drive pawl ineffective as the ratchet wheel driving means during the oscillatory movement of said armature and when said second electromagnet is in its energized position the stud renders said forward drive pawl ineffective as the ratchet wheel driving means during the oscillatory movement of said armature, and a detenting means adapted to coact with said ratchet wheel to prevent retrograde movement thereof.

3. In a secondary clock of the electrical impulse type, the combination of a two-core magnet unit, an oscillatable armature mounted on a shaft between the cores of said unit and so disposed as to be rotated into substantially parallel relationship with lines of magnetic flux when said magnet unit is energized, a disc rigidly fixed to the end of said shaft, a helical spring fixed to the periphery of said disc for retracting the armature when said magnet unit is de-energized, a time indicating shaft, a square-toothed ratchet wheel rigidly attached to said time indicating shaft, a pair of drive pawls pivotally mounted on said disc and adapted to coact with said ratchet wheel for driving the same incrementally in either a forward or reverse direction in response to the movement of said armature between its normal and energized positions, an electromagnet and means for selectively energizing the electromagnet, a pivotally mounted lever associated with said electromagnet and adapted to be actuated in response to the energization and de-energization of said electromagnet, and a stud mounted on said lever which normally projects into the path of movement of one of said drive pawls as the latter moves with said armature between its normal and energized positions thereby preventing the drive pawl from engaging with said ratchet wheel in driving relationship during the oscillatory movement of said armature and when said electromagnet is energized said stud projecting into the path of movement of the other of said drive pawls as the latter moves with said armature between its normal and energized positions thereby preventing drive pawl from engaging with said ratchet wheel in driving relationship during the oscillatory movement of said armature.

4. In a secondary clock of the electrical impulse type, the combination of a two-core magnet unit, an oscillatable armature mounted on a shaft between the cores of said unit and so disposed as to be rotated into substantially parallel relationship with lines of magnetic flux when said magnet unit energized, a disc rigidly fixed to the end of said shaft, a helical spring fixed to the periphery of said disc for retracting the armature when said magnet unit is de-energized, a time indicating shaft, a square-toothed ratchet wheel rigidly attached to said

time indicating shaft, a pair of drive pawls pivotally mounted on said disc and adapted to coact with said ratchet wheel to rotate the latter incrementally in either a forward or reverse direction in response to the movement of said armature between its normal and energized positions, an electromagnet and means for selectively energizing the electromagnet, a lever pivotally mounted on said time indicating shaft and adapted to be actuated in response to the energization and de-energization of said electromagnet, a stud mounted on said lever which normally projects into the path of movement of one of said drive pawls as the latter moves with the armature between its normal and energized positions thereby preventing the drive pawl from engaging with said ratchet wheel and driving same in a reverse direction during the oscillatory movement of said armature, and a detenting means adapted to coact with said ratchet wheel to prevent retrograde movement thereof.

5. In a secondary clock of the electrical impulse type, the combination of a two-core magnet unit, an oscillatable armature mounted on a shaft between the cores of said unit and so disposed as to be rotated into substantially parallel relationship with lines of magnetic flux when said magnet unit is energized, a disc rigidly fixed to the end of said shaft, a helical spring fixed to the periphery of said disc for retracting the armature when said magnet unit is de-energized, a time indicating shaft, a square-toothed ratchet wheel rigidly attached to said time indicating shaft, a forward drive pawl and a reverse drive pawl pivotally and eccentrically mounted on said disc and adapted to coact with said ratchet wheel to rotate the latter incrementally in response to the movement of said armature between its normal and energized positions, an electromagnet and means for selectively energizing the electromagnet, a lever pivotally mounted on said time indicating shaft and adapted to be actuated in response to the energization and de-energization of said electromagnet, and a stud mounted on said lever and positioned relative to said drive pawls whereby when said electromagnet is in its normal de-energized position the stud renders said reverse drive pawl ineffective as the ratchet wheel driving means during the oscillatory movement of said armature and when the electromagnet is in its energized position the stud renders said forward drive pawl ineffective as the ratchet wheel driving means during the oscillatory movement of said armature.

6. In a secondary clock of the electrical impulse type, the combination of a two-core magnet unit, an oscillatable armature mounted on a shaft between the cores of said unit and so disposed as to be rotated into substantially parallel relationship with lines of magnetic flux when said magnet unit is energized, a disc rigidly fixed to the end of said shaft, a helical spring fixed to the periphery of said disc for retracting the armature when said magnet unit is de-energized, a time indicating shaft, a square-toothed ratchet wheel rigidly attached to said time indicating shaft, a forward drive pawl and a reverse drive pawl pivotally and eccentrically mounted on said disc and adapted to coact with said ratchet wheel to rotate the latter incrementally in response to the movement of said armature between its normal and energized positions, an electromagnet and means for selectively energizing the electromagnet, a lever pivotally mounted on said time indicating shaft and adapted to be actuated in response to the energization and de-energization of said electromagnet, a stud mounted on said lever and positioned relative to said drive pawls whereby when said electromagnet is in its normal de-energized position the

stud renders said reverse drive pawl ineffective as the ratchet wheel driving means during the oscillatory movement of said armature and when the electromagnet is in its energized position the stud renders said forward drive pawl ineffective as the ratchet wheel driving means during the oscillatory movement of said armature, and a detenting means adapted to coact with said ratchet wheel to prevent retrograde movement thereof.
